AIR-COMPRESSOR.

1,248,119.

Specification of Letters Patent. Patented Nov. 27, 1917.

Application filed May 8, 1912. Serial No. 695,876.

To all whom it may concern:

Be it known that I, FRED D. HOLDSWORTH, a citizen of the United States, and a resident of Claremont, county of Sullivan, and State 5 of New Hampshire, have invented an Improvement in Air-Compressors, of which the following description, in connection with the accompanying drawings, is a specification, like characters on the drawings representing 10 like parts.

This invention relates to elastic fluid compressors, and is applicable to the low-pressure cylinder of a multi-stage compressor, or to the cylinder of a single-stage 15 compressor, or to any cylinder beyond the intake cylinder of a multi-stage compressor.

In the operation of air compressors which are driven by an external source of power which runs at a constant speed, such as electric motors, gas or gasoline engines, in order 20 to maintain a constant pressure, it is necessary to interrupt the flow of air through the machine when the pressure in the receiver reaches the desired point, and reestablish 25

the flow as soon as the pressure in the receiver has fallen a few pounds. This is usually accomplished by placing a balanced 30 valve, commonly called an unloading valve, on the main inlet supply to the compressor, and attaching to this valve a suitable piston, which moves the valve to its open or closed position by means of a small regulator which is piped to the main air receiver. When 35 this unloading valve is closed by the rise in the receiver pressure, the compressor rapidly forms a more or less complete vacuum in all of its internal air passages. Owing to the construction of this form of unloading valve, it is impossible to make it absolutely 40 air-tight when it is closed, so that a small quantity of air flows through the machine, which air has to be compressed and applied to the main receiver. Instead of compressing 45 this air from ordinary atmospheric pressure, it may be compressed from only one or two pounds pressure up to receiver pressure. This greatly increases the ratio of compres- 50 sion, and as the heat generated in compres- sion is directly dependent upon the number of times the air is compressed, it will readily be seen that when the air reaches its final pressure in the air cylinder, it will be heated very much in excess of the temperature ob-

tained in compression under normal running conditions with the inlet opening wide 55 open. This temperature is detrimental to the oil used for lubrication, and is a source of danger, inasmuch as the extreme heat may ignite the oil, and if the oil is diffused through the air in proper proportions an 60 explosion may result. This is especially true of multi-stage compressors where the pressure is carried to several hundred pounds per square inch. This invention is more particularly concerned with the pro- 65 vision of an unloading valve which may be employed in connection with the second or high-pressure cylinder of a two-stage compressor, or the second and third cylinders of a three-stage compressor, or with the suc- 70 ceeding cylinders of a compressor of any desired number of stages, and with slight modification may be applied to the low-pressure cylinder of a multi-stage compressor or to the cylinder of a single-stage com- 75 pressor.

In my copending application, Serial No. 695,875, of even date herewith, I have disclosed an elastic fluid compressor similar in its general characteristics to my present in- 80 vention, but specifically different therefrom, the present application, however, being in- tended to dominate said copending applica- 85 tion. Specifically, the present application is distinguished from the companion appli- 90 cation in that, in the latter, the auxiliary unloading valve is seated by the pressure in the intake plus that of a spring, while in the present case, the pressure in the outlet plus a spring is applied to seat the valve. 95

My invention will be best understood by reference to the following description, when taken in connection with the accompanying illustration of one specific embodiment thereof, while its scope will be more par- 100 ticularly pointed out in the appended claims:

In the drawings:-

Figure 1 is a central longitudinal vertical section partly in elevation of a compressor embodying my invention;

Fig. 2 is a cross-sectional view of the compressor on line 2—2 of Fig. 1;

Fig. 3 is a longitudinal vertical section on an enlarged scale of one end of the cylinder succeeding the low-pressure cylinder of a multi-stage compressor, and which cylin- 105

der in the present embodiment is of the double-acting type, the front end being precisely similar in construction. This view shows the position of the auxiliary unloading valve under normal running conditions;

Fig. 4 is a sectional view partly in elevation, similar to Fig. 3, showing the auxiliary unloading valve as it appears when the main unloading valve closes; and

Fig. 5 is a sectional view showing a modification of a portion of the valve mechanism.

Referring to the drawings, and to the embodiment of my invention which I have there disclosed for illustrative purposes, I have there shown a multi-stage compressor herein having two cylinders, a low-pressure cylinder 6 and a high-pressure cylinder 7, the former drawing its supply from an inlet pipe 8 into an inlet chamber 9, and delivering the compressed air into an outlet chamber 10 connected by a pipe 11 to an intermediate receiver 12, which as usual cools the air before it passes to the high-pressure cylinder. This receiver, which is commonly called an inter-cooler, delivers the air into an inlet chamber 13 of the high pressure cylinder 7, whence it passes to an outlet chamber 14, as will appear hereinafter. This outlet chamber in practice is connected to a main receiver which I have not shown herein, as it unnecessary to the illustration of my present invention. The main inlet 8 may be controlled as is usual by means of a main unloading valve 15 of the balanced type. This valve is usually controlled by a suitable piston, which moves to its open or closed position by means of a small regulator, which is piped to the main air receiver, these parts being of usual and well-known construction, and a further description of them being unnecessary to an understanding of my present invention.

The auxiliary unloading valve which forms the subject matter of my present invention may be applied to any cylinder of a multi-stage compressor. In the form illustrated in Figs. 1 to 4 inclusive, it is shown as applied to any cylinder beyond the first, or low-pressure cylinder,—that is to say, it may be applied to the second or high-pressure cylinder of a two-stage compressor, or to the second and third cylinders of a three-stage compressor; while Fig. 5 shows a slight modification which I have made to adapt the auxiliary unloading valve to the low-pressure cylinder of a multi-stage compressor, or to the cylinder of a single-stage compressor.

Referring now to Figs. 3 and 4, I have there shown one end of the high-pressure cylinder 7, herein of the double-acting type, the other end being precisely similar in construction. This cylinder is provided with a head 16, in which is located an inlet valve 17, which may be of any usual or desired

construction, the same being herein of the oscillating type, being given an oscillating motion at the proper intervals in the operation of the machine by suitable mechanism connected with the crank shaft (see Fig. 1). The cylinder is also provided as usual with one or more discharge valves 18, which may be of any usual construction, herein being provided with a spring 19 tending to seat the same and operating as usual to open and permit the air compressed in the cylinder to flow into the outlet chamber 14 and thence to the usual main air receiver.

Within the cylinder 7 is a usual piston 20, which when moved toward the right (Fig. 3) draws the air through the inlet chamber 13 and its connections with the low-pressure cylinder 6, and upon the closing of the inlet valve 17, as shown in Fig. 4, the piston moves toward the left, thereby compressing the air in the usual manner. When the pressure in the cylinder is equal to, or slightly greater than, the pressure in the discharge chamber 14, the discharge valve 18 will lift from its seat to allow the air to be forced out of the cylinder.

To prevent the formation of a more or less complete vacuum when the unloading valve 15 on the main inlet 8 closes, I have provided a valve 21 which is adapted to open or close the port 22 leading from the interior of the cylinder 7 to the inlet chamber 13. This valve may be of any suitable construction, but I have herein chosen to employ for this purpose a hollow shell, which is guided on a suitable guide, herein a plug 23. Suitable means are provided for establishing a communication between the interior of the valve 21 and the outlet chamber 14, so as to normally allow the pressure within said outlet chamber to be exerted on said valve in such a manner as to tend to seat the same. For this purpose, the plug 23 is made hollow and its interior is connected by a pipe 24 to a small auxiliary cylinder 25. This auxiliary cylinder is connected by a pipe 26 to the outlet chamber 14. Located within the auxiliary cylinder 25 is a valve 27, herein of the piston type, having a reduced portion 28 intermediate its ends. When the compressor is operating under normal conditions, the discharge air pressure in the outlet chamber 14 is communicated through the pipe 26 around the reduced portion 28 of the valve 27 to the pipe 24, and thence to the interior of the plug 23 and valve 21, thereby tending to seat the latter. This pressure may be assisted if desired by means of a suitable spring 29, tending to seat the valve 21. In the case of a double-acting cylinder, the pipe 24 has a branch 30 leading to a similar construction at the opposite end of the cylinder. Inasmuch as the internal diameter of the valve 21 is somewhat greater

than the diameter of the port 22, said valve will not rise from its seat, since the total pressure holding it against its seat will be greater than that tending to raise it, for the 5 reason that the pressure in the interior of the compressor cylinder is never greater than that in the discharge space 14. One end of the auxiliary cylinder 25 is placed in communication with the inlet space 13 10 of the cylinder, herein by a pipe 31. When the unloading valve on the main inlet to the low-pressure cylinder closes, air is no longer delivered to the cylinder in question, and as the latter continues to draw air from 15 the space 13, the pressure in this space begins to fall. This space being in communication with one end of the auxiliary cylinder 25, as just described, the drop in pressure soon reaches a point where the pressure 20 acting against the end of the piston valve or plunger 27 is no longer sufficient to hold the latter in the position shown in Fig. 3 against the pressure of the spring 32 bearing against the opposite end of the 25 plunger. Accordingly, the plunger is forced over toward the right under the influence of the spring into the position shown in Fig. 4. When the valve is in this position, the supply of air from the discharge space 30 14 to the interior of the valve 21 is cut off, and communication between the interior of said valve and the atmosphere is established through the pipe 24, the cylinder 25 and a vent opening 33. The pressure still remaining 35 in the inlet space 13 and within the interior of the cylinder 6 will then be sufficient to force the valve 21 from its seat, after which it is evident that no air will be discharged from this cylinder into the 40 discharge space 14, but will return through the cylinder to the admission space 13 through the port 22.

When the unloading valve on the inlet of the low pressure cylinder again opens, 45 this cylinder will begin to deliver air to the inlet space 13. This pressure will be communicated through the pipe 31 to the right-hand end of the piston or plunger 27, and when a sufficiently high pressure is reached, 50 the latter will be forced back again into the position shown in Fig. 1, whereupon pressure will be admitted to the interior of the valve 21, closing it, after which the normal function of compression will be resumed. In case it is desired to attach the 55 auxiliary unloading valve hereinbefore described to the low-pressure cylinder of a multi-stage compressor, or to the cylinder of a single-stage compressor, a slight modification may be made, as shown in Fig. 5, in 60 which the spring, herein a spring 34 similar to the spring 32, is applied to the opposite end of the cylinder from that to which the spring 32 is applied, as shown in Fig. 3. In 65 other respects, the apparatus will remain

unchanged in its adaptation to the low-pressure cylinder of a multi-stage compressor or to the cylinder of a single-stage compressor. Assuming that the unloading valve on the main inlet closes, a partial vacuum will 70 be set up in the inlet space 13. Inasmuch as the left-hand end of the plunger shown in Fig. 5 is exposed to atmospheric pressure through the vent-hole to the atmosphere, as soon as a sufficient diminution of the atmosphere below atmospheric pressure has been reached, the plunger will be forced toward the right, thereby cutting off the supply of pressure from the discharge space through the pipe 26, and the interior of the 75 valve 21 will then be connected with the atmosphere through the pipe 24, the interior of the cylinder 25 and the vent-hole 33. The air which may remain in the inlet 13 and which is drawn into the cylinder, will be 80 forced out through the port 22, before it reaches a pressure very much in excess of atmospheric pressure, because of the fact that only atmospheric pressure is now existing in the interior of the valve 21. This will 85 avoid the high ratio of compression on any air remaining in the interior of the cylinder or the passages leading thereto. While I have shown the application of these methods of unloading as applied to a single- 90 stage compressor or the low-pressure cylinder of a multi-stage compressor, I consider the auxiliary unloading valve especially desirable for attachment to the cylinder succeeding the low-pressure cylinder of the latter type of compressor. It will be understood from the foregoing that the auxiliary unloading valve acts automatically to prevent diminution of pressure in the connections between the high and low-pressure cylinders to a point below atmospheric pressure when the main unloading valve closes, or in other words, the auxiliary valve acts 95 automatically to place the high-pressure cylinder in communication with the connections between the cylinders when the pressure within the said connections falls below normal. 100

While I have herein shown and described two forms of my invention for illustrative purposes, and have disclosed and discussed in detail the construction and arrangement incidental to two specific embodiments thereof, it is to be understood that the invention is limited neither to the mere details or relative arrangement of parts, nor to the specific embodiments herein shown, but that extensive deviations from the illustrated forms or embodiments of the invention may be made without departing from 110 the principles thereof. 115

I claim:

1. In an elastic fluid compressor, the combination with means for drawing in and compressing the fluid, said means having an 120

- intake valve; of a valve for controlling the supply of fluid to the compressing means; connections between said valves; and means distinct from said intake valve and actuated by the pressure in said compressing means effective to prevent diminution of pressure to a point below atmospheric pressure within said connections when the second-mentioned valve closes.
2. In an elastic fluid compressor, the combination with fluid compressing means having a mechanically actuated inlet valve and an outlet valve; of a valve controlling the supply of fluid to said inlet valve; connections between said controlling valve and said inlet valve; and means distinct from said inlet valve and actuated by the pressure in said compressing means, to prevent diminution of pressure within said connections to a point below atmospheric pressure.
3. In an elastic fluid compressor, the combination with fluid compressing means; of an unloading valve for controlling the supply of fluid to the compressing means; and an auxiliary unloading valve opened by the pressure within said compressing means, for relieving the condition of pressure within the compressing means when the first-mentioned unloading valve closes.
4. In an elastic fluid compressor, the combination with fluid compressing means having an intake valve; of an unloading valve for controlling the supply of fluid to the compressing means; and an auxiliary unloading valve distinct from said intake valve and opened by the pressure within said compressing means, for preventing diminution of pressure within the connections between the first-mentioned unloading valve and the compressing means to a point below atmospheric pressure.
5. In an elastic fluid compressor, the combination with fluid compressing means having a mechanically actuated inlet valve and a pressure-fluid opened outlet valve; of an unloading valve for controlling the supply of fluid to the compressing means; and an auxiliary unloading valve operated by the pressure within said compressing means, for preventing diminution of pressure within the connections between the first-mentioned unloading valve and said inlet valve to a point below atmospheric pressure.
6. In an elastic fluid compressor, the combination with fluid compressing means; of an unloading valve for controlling the supply of fluid to the compressing means; and a valve seated by the pressure in the outlet and opened by the pressure within said compressing means, for relieving the condition of pressure within the compressing means when the unloading valve closes.
7. In an elastic fluid compressor, the combination with fluid compressing means; of an unloading valve for controlling the supply of fluid to the compressing means; and a valve seated by the pressure in the outlet and opened by the pressure within said compressing means, for preventing diminution of pressure within the connections between the first-mentioned unloading valve and the compressing means to a point below atmospheric pressure.
8. In an elastic fluid compressor, the combination with fluid compressing means; of an unloading valve for controlling the supply of fluid from the inlet to the compressing means; an unloading valve normally closed by pressure in the outlet and subject to pressure within said compressing means; and means rendered effective by reduction of pressure in the connections between the first-mentioned unloading valve and the compressing means, to cut off the pressure tending to seat the second-mentioned unloading valve and permit the latter to open under the influence of pressure within the compressing means.
9. In an elastic fluid compressor, the combination with a cylinder and piston, of admission and outlet valves for said cylinder, an unloading valve for controlling the supply of fluid to the admission valve, said cylinder having an outlet port leading to the connections between said unloading and admission valves, a valve for said port normally seated by pressure in the outlet and subject to the pressure within said cylinder, and means rendered effective by a reduction of pressure in said connections to cut off the pressure tending to seat the last-mentioned valve and permit the latter to open under the influence of the pressure within said cylinder.
10. In an elastic fluid compressor, the combination with a cylinder and piston, of admission and outlet valves for said cylinder, an unloading valve for controlling the supply of fluid to the admission valve, said cylinder having an outlet port leading to the connections between said unloading and admission valves, a valve for said port normally seated by pressure in the outlet and subject to the pressure within said cylinder and means including a valve normally held open by the pressure in said connections and adapted to be released by a reduction of the pressure in said connections thereby to close under atmospheric pressure and cut off the pressure tending to seat the valve of said port.
11. In an elastic fluid compressor, the combination with a cylinder and piston, of admission and outlet valves for said cylinder, an unloading valve for controlling the supply of fluid to the admission valve, said cylinder having an outlet port leading to the connections between said unloading and admission valves, a valve for said port normally seated by pressure in the outlet and subject to the pressure within said cylinder.

der, a valve adapted to control the pressure tending to seat the valve of said port, and means actuated by a reduction of the pressure in said connections to allow the last-mentioned valve to close and cut off the pressure tending to seat the valve of said port.

12. In an elastic fluid compressor, the combination with a cylinder and piston, of admission and outlet valves for said cylinder, an unloading valve for controlling the supply of fluid to the admission valve, said cylinder having an outlet port leading to the connections between said unloading and admission valves, a valve for said port normally seated by pressure in the outlet and subject to the pressure within said cylinder, a valve adapted to control the pressure tending to seat the valve of said port, a spring tending to close the last-mentioned valve, and means actuated by a reduction of the pressure in said connections to allow the last-mentioned valve to close and cut off the pressure tending to seat the valve of said port.

13. In an elastic fluid compressor, the combination with a cylinder and piston, of admission and outlet valves for said cylinder, an unloading valve for controlling the supply of fluid to the admission valve, said cylinder having an outlet port leading to the connections between said unloading and admission valves, a valve for said port normally seated by pressure in the outlet and subject to the pressure within said cylinder, a valve adapted to control the pressure tending to seat the valve of said port, and a valve-actuating piston connected to the last-mentioned valve acting under normal conditions to hold said valve open but adapted to be actuated by a reduction of the pressure in said connections to allow the valve controlled thereby to close and cut off the pressure tending to seat the valve of said port.

14. In an elastic fluid compressor the combination with a cylinder and piston, of admission and outlet valves for said cylinder, an unloading valve for controlling the supply of fluid to the admission valve, said cylinder having an outlet port leading to the connections between said unloading and admission valves, a valve for said port normally seated by pressure in the outlet and subject to the pressure within said cylinder, a piston valve adapted to control the pressure tending to seat the valve of said port, and a cylinder for said piston valve having one end in communication with said connections and the other end in communication with the atmosphere.

15. In an elastic fluid compressor, the combination with a cylinder and piston, of admission and outlet valves for said cylinder, an unloading valve for controlling the supply of fluid to the admission valve, said

cylinder having an outlet port leading to the connections between said unloading and admission valves, a valve for said port normally seated by pressure in the outlet and subject to the pressure within said cylinder, a piston valve adapted to control the pressure tending to seat the valve of said port, a cylinder for said piston valve having one end in communication with said connections and the other end in communication with the atmosphere, and a spring tending to move said piston valve into position to cut off the pressure tending to seat the valve of said port.

16. In an elastic fluid compressor, the combination with fluid compressing means; of a valve for controlling the supply of fluid to the compressing means; connections between said valve and said compressing means; and means including a valve subject to and opened by pressure within said compressing means, to prevent diminution of pressure to a point below normal inlet pressure within said connections when said valve closes.

17. In an elastic fluid compressor, the combination with fluid compressing means; of means forming an inlet space; inlet controlling means; and automatic means including a valve subject to and opened by pressure within said compressing means, for releasing pressure fluid from the compressing means to the inlet space when said inlet is closed.

18. In an elastic fluid compressor, the combination with fluid compressing means; of fluid supply means having a supply space; controlling means for said supply means; and automatic means including a device subject to and rendered effective by pressure within said compressing means when said supply means is closed, for bypassing from the compressing means to said supply-space pressure fluid previously drawn from said supply space.

19. In an elastic fluid compressor, the combination with compressing means for drawing in and compressing the fluid, said compressing means having a periodically opening and closing intake valve and a discharge valve, of fluid conducting means for conducting the supply of fluid to said compressing means, and automatic means separate from said intake and discharge valves and subject to and opened by pressure within said compressing means for releasing pressure fluid therefrom into said fluid conducting means.

20. In a multi-stage elastic fluid compressor, the combination with a plurality of compressor units acting successively to compress the elastic fluid, of a periodically opening and closing intake valve and a discharge valve for the high pressure unit, and means independent of said intake and dis-

charge valves and subject to and opened by pressure within said compressing means for returning into the connection between said units elastic fluid that is drawn through said 5 intake valve.

21. In a multi-stage elastic fluid compressor, the combination with a plurality of compressor units, one delivering to another, and each having an intake valve arranged 10 to open and close periodically, of a main unloading valve for the first stage compressor unit, and a high pressure unloading valve independent of the high pressure unit intake valve and subject to and rendered 15 effective by the pressure within the high pressure unit.

22. In an elastic fluid compressor, a cylinder, a piston, inlet and discharge valves for 20 said cylinder, an unloading valve, a connection between the latter and said inlet valve, a valve actuated by pressure in said cylinder controlling the communication between the latter and said connection, and controlling means for said valve responsive to variations in pressure in said connection.

23. In an elastic fluid compressor, a cylinder, a piston, inlet and discharge valves for 30 said cylinder, an unloading valve, a connection between the latter and said inlet valve, a pressure actuated valve in said cylinder 35 controlling the communication between the latter and said connection, and controlling means for said valve responsive to variations in pressure in said connection for supplying pressure fluid thereto from said cylinder.

24. In an elastic fluid compressor, a cylinder, a piston, inlet and discharge valves for 40 said cylinder, an unloading valve, a connection between the latter and said inlet valve, a valve responsive to pressure in said cylinder 45 controlling the communication between the latter and said connection, and controlling means for said valve responsive to a drop in pressure in said connection below atmospheric pressure.

25. In an elastic fluid compressor, a cylinder, a piston, inlet and discharge valves for 50 said cylinder, an unloading valve, a connection between the latter and said inlet valve, a pressure actuated valve in said cylinder 55 controlling the communication between the latter and said connection, and controlling means for said valve responsive to a drop in pressure in said connection below atmospheric pressure for supplying pressure fluid thereto from said cylinder.

26. In a multi-stage elastic fluid compressor, the combination with a plurality of compressor units acting successively to 60 compress the elastic fluid, and a main unloading valve, of a valve for the inlet of a high pressure compressor unit, and means independent of said valve automatically to prevent diminution of pressure to a point 65 below atmospheric pressure in the connections

between said compressor units upon a predetermined increase in pressure in said high pressure compressor unit.

27. In a multi-stage elastic fluid compressor, the combination with a plurality of 70 compressor units one delivering to another, of a main unloading valve for the inlet of the first-stage compressor unit, and an auxiliary unloading valve for the succeeding compressor unit discharging into the connections between said units when the pressure in said last mentioned unit exceeds a predetermined amount.

28. In a multi-stage elastic fluid compressor, the combination of a plurality of compressor units, one delivering to another, of a main unloading valve for the inlet of the first-stage compressor unit, an inlet valve 80 for the succeeding compressor unit, and means subject to pressure within said succeeding compressor unit automatically to prevent diminution of pressure to a point 85 below atmospheric pressure in the connections between said compressor units when the main unloading valve closes.

29. In a multi-stage elastic fluid compressor, the combination of a plurality of compressor units each having a cylinder and a piston, and one delivering to another, of a valve for the inlet of one of said compressor 95 units, an inlet valve for the succeeding compressor unit, and means subject to pressure within said compressor unit automatically to place the cylinder of said succeeding compressor unit in communication with the connections between the compressor units when the pressure in said connections falls below normal.

30. In a multi-stage elastic fluid compressor, the combination of a plurality of compressor units, each having a cylinder and a piston, and one delivering to another, of an unloading valve for the inlet of one of said compressor units, an inlet valve for the 105 succeeding compressor unit, the cylinder of 110 said succeeding compressor unit having a port communicating with the connections between the compressor units, a valve for 115 said port, and means normally holding the last mentioned valve seated and adapted to permit said valve to open when the pressure in said cylinder rises above a predetermined amount.

31. In a multi-stage elastic fluid compressor, the combination of a plurality of compressor units each having a cylinder and a piston, and one delivering to another, of an unloading valve for the inlet of one of said compressor units, an inlet valve for the succeeding compressor unit, the cylinder of 120 said succeeding compressor unit having a port communicating with the connections between the compressor units, a valve for 125 said port responsive to cylinder pressure, a piston for controlling the last mentioned 130

valve, and a cylinder for said valve-actuating piston communicating on one side of the latter with the atmosphere and on the other side with said connections.

5 32. In a multi-stage elastic fluid compressor, the combination of a plurality of compressor units each having a cylinder and a piston, and one delivering to another, of an unloading valve for the inlet of one of said

10 compressor units, an inlet valve for the succeeding compressor unit, the cylinder of said succeeding compressor unit having a port communicating with the connections between the compressor units, a valve for

15 said port responsive to cylinder pressure, a piston for controlling the last mentioned valve, a cylinder for said valve-actuating piston communicating on one side of the latter with the atmosphere and on the other

20 side with said connections, and a spring normally tending to seat the last mentioned valve.

33. In an elastic fluid compressor, the combination with compressing means for drawing in and compressing the fluid, said compressing means having an intake valve, of controlling means for controlling the supply of fluid to said compressing means, and automatic means separate from said intake

25 valve for releasing pressure fluid from said compressing means into the connections between said controlling means and said compressing means when the pressure in said compressing means exceeds a predetermined

30 amount.

34. In an elastic fluid compressor, the combination with compressing means for drawing in and compressing the fluid, said compressing means having a periodically opening and closing positively operated intake valve and a discharge valve, of fluid conducting means for conducting the supply of fluid to said compressing means, and automatic means separate from said intake and

40 discharge valves and actuated by the pressure in said compressing means for releasing pressure fluid from said compressing means into said fluid conducting means.

35. In a multi-stage elastic fluid compressor, the combination with a plurality of compressor units acting successively to compress the elastic fluid, of a periodically opening and closing positively operated intake valve and a discharge valve for the high pressure unit, and means independent of said intake and discharge valves and actuated by the pressure in said high pressure unit to by-pass back into the connections between said units elastic fluid that is drawn

45 through said intake valve.

36. In a multi-stage elastic fluid compressor, the combination with a plurality of compressor units one delivering to another and each having a positively operated in-

take valve arranged to open and close periodically, of a main unloading valve for the first-stage compressor unit, and a high pressure unloading valve independent of the high pressure unit intake valve and subject to pressure within the high pressure unit and opened thereby after closure of said main unloading valve.

37. In an elastic fluid compressor, in combination, a compression cylinder, a mechanically actuated inlet valve and a spring held outlet valve therefor, an unloading valve for controlling the supply of fluid to said cylinder, an auxiliary unloading valve communicating with said cylinder and subject to the pressure therein, and means to apply fluid pressure to seat said valve, said means acting to reduce said pressure to release said valve when the pressure in the cylinder has changed undesirably because of the action of the first mentioned unloading valve.

38. In an elastic fluid compressor, a cylinder and piston, separate inlet and discharge valves for said cylinder, an unloading valve, a connection between the same and said inlet valve, a valve in said cylinder controlling the communication between the latter and said connection, a second cylinder receiving fluid discharged from said discharge valve, a second piston working in said second cylinder having one end exposed to atmospheric pressure, means for connecting the opposite end of said second cylinder to said connection, and means controlled by said second piston communicating with the valve controlling the communication between said first cylinder and said connection.

39. In an elastic fluid compressor, a cylinder and piston, inlet and discharge valves for said cylinder, an unloading valve, a connection between the same and said inlet valve, a valve in said cylinder controlling the communication between the latter and said connection, a second cylinder receiving fluid from said discharge valve, a second piston working in said cylinder having one end exposed to atmospheric pressure, means for connecting the opposite end of said second cylinder to said connection, means controlled by said second piston communicating with the valve controlling the communication between said first cylinder and said connection, and cooperating resilient means for impelling said second piston in one direction.

In testimony whereof, I have signed my name to this specification, in the presence of two subscribing witnesses.

FRED D. HOLDSWORTH.
